SKILLET-GRILL, OR SIMILAR ARTICLE

John Behm, Santa Ana, Calif., assignor to National Silver Company, New York, N.Y.

Filed June 14, 1971, Ser. No. 153,150

Term of patent 14 years

Int. Cl. D7—02

U.S. Cl. D44—1 J

FIG. 1 is a top plan view of a skillet-grill or similar article showing my new design;

FIG. 2 is a bottom plan view thereof;

FIG. 3 is a longitudinal section on the line 3—3 of FIG. 1;

FIG. 4 is a transverse section on the line 4—4 of FIG. 1; and

FIG. 5 is a transverse section on the line 5—5 of FIG. 1.

I claim:

The ornamental design for a skillet-grill, or similar article, as shown.
